UNITED STATES PATENT OFFICE.

JOSEPH STANLEY STOGDALE, OF TACOMA, WASHINGTON.

MECHANICAL STOKER.

Application filed May 26, 1921. Serial No. 472,878.

To all whom it may concern:

Be it known that I, JOSEPH STANLEY STOGDALE, a citizen of the United States, and a resident of the city of Tacoma, county 5 of Pierce, State of Washington, have invented certain new and useful Improvements in Mechanical Stokers, of which the following is a specification.

My invention relates to improvements in 10 mechanical stokers, more particularly to stokers of that character designed for use in connection with railway locomotive or similar stationary engines; the principal object of the present invention being to 15 provide a mechanical stoker for delivering fuel from the tender of a railway locomotive into the fire box of the locomotive boiler.

It is a further object of the invention to 20 provide means of the above character adapted to maintain a supply of coal in paired hoppers, from which it is mechanically fed through paired doors of the fire box of such locomotives, and distributed over the fire bed.

25 Other objects of the invention reside in the details of construction of the feeding mechanism whereby the fuel is caused to be distributed equally over all parts of the fire bed.

30 In accomplishing these and other objects of the invention, I have provided the improved details of construction, the preferred forms of which are illustrated in the accompanying drawings, wherein—

35 Figure 1 is a vertical, sectional view longitudinally through a stoker constructed according to the present invention.

Figure 2 is a rear view of the same taken on the line 2—2 in Figure 1.

40 Figure 3 is a side view of a stoker housing; a spring housing being shown in section for better illustration.

Figure 4 is a longitudinal, vertical section of the same.

45 Figure 5 is a side view of the stoker, opposite that side shown in Figure 3; with a spring housing shown in section for better illustration.

Figure 6 is a plan view of one of the 50 stoker housings, the top of which is removed to show the construction, and operation of the discharge plate.

Figure 7 is a perspective view of a feeding shovel.

55 Referring more in detail to the several views of the drawings, wherein like refer-

ence numerals designate the same or like parts—

1 designates what may be the fire box of a locomotive boiler 2, and 3 designates, as 60 a whole, a tender drawn by the locomotive, and wherein coal, or other fuel, is carried. The fire box 1 is provided with double doors or openings 4—4' through which fuel may be fed into the same, and below these has 65 other openings closed by doors 5, through which inspection of the boiler or other work may be done.

Extending horizontally, from the lower part of the tender, forwardly and into the 70 cab of the locomotive is a cylindrical conveyer tube 8, provided at the end within the tender with an opening 9 through which coal may be admitted into the tube and at its forward end with an opening into a 75 connecting tube 10 that leads into the lower end of a vertical conveyer tube 12. This latter tube discharges at its upper end into paired hoppers 13 and 14, at opposite sides thereof, and from which the fuel delivered 80 thereto may flow by gravity into stoker boxes 15 and 16 which are closed at their outer ends and at their other ends open respectively through the doors or openings 4 and 4' into the fire box 1. 85

Mounted functionally within the conveyer tubes 8 and 12 respectively, are worm conveyers 17 and 18, the drive shafts 19 and 20 of which extend from the adjacent ends of the tubes and are equipped with intermeshing bevel gears 21 and 22 so that they may operate together. The gear 21 has a gear wheel 23 formed thereon which meshes with a driving gear 24 fixed on a motor shaft 25 that is mounted in suitably supported 90 bearings 26 and 27. This shaft may be driven by any suitable means, which may be a small steam driven engine, or direct driving connection with the locomotive axle, or other operating parts, whereby it would be 95 revolved continuously in the same direction.

Coal delivered into the hoppers, will flow by gravity into the stoker boxes 15 and 16 where it is delivered onto horizontal shelves 30, to be delivered therefrom in certain desired amounts, by the reciprocal movement of feeding plates 31 slideable on the shelves, onto the lower floors of the boxes, from which it is then discharged into the fire box by the action of shovels 32 presently described. 105

The means provided for actuating the delivery plates 31 and shovels 32 comprises a 110

shaft 35 which extends horizontally through the stoker boxes as shown best in Figures 1 and 2 and which is rotatably driven by means of a vertical shaft 36 which is mounted in front of the conveyer 12. At its lower end this shaft has a bevel gear wheel 37 thereon which meshes with a similar gear wheel 38 on the shaft 25, and at its upper end has a worm gear 39 meshing with a gear 40 on the shaft 35; the connection being such that the latter shaft is rotated in the direction of the arrow in Figures 3 and 5.

Keyed onto the shaft 35 at the right hand sides of the stoker boxes, as shown in Figure 2, are wheels 45, each comprising a plurality of radially extending arms 45' of different lengths, and secured on the shaft at the opposite sides of the boxes are wheels 46, similar to the wheels 45, but having radiating arms 46' all of the same length.

The discharge plates 31 are adapted to slide longitudinally upon the shelves 30 across and from the openings of the hoppers and at their forward ends are provided with slightly wedge shaped nose plates 31' whereby, when they move forwardly, the coal that has been fed onto the shelves, is scattered and pushed from the shelves onto the lower floors of the boxes.

The means provided for reciprocating the plates comprises levers 50 which extend horizontally through slots 51 in the side walls of the stoker boxes, and at their outer ends are pivotally fixed upon brackets 52 extended laterally from the boxes. The inner ends of these levers are free to move between spaced flanges 53 and 54 fixed to the plates and the levers are actuated forwardly and rearwardly to move the plates likewise, by means of connecting rods 55, fixed pivotally thereto at the rearward ends, and at the forward ends to the lower end portions of levers 56 that are pivotally mounted by pins 57 upon the sides of the boxes to extend in such position that these ends will be engaged by the arms 46' of the wheels 46 as the latter are rotated by the shaft 35.

The plates are moved to and normally retained at their forward limits of travel, 50 and across the hopper openings, by means of compression springs 59 which are contained within tubes 60 mounted on the forward ends of the sides of the boxes, and which by means of rods 61 are connected 55 with the upper ends of the levers 56.

It will be apparent that rotation of the shaft 35 will cause the arms of the wheels 46 to engage the lower ends of the levers 56 to move the latter rearwardly and in doing so will cause the plates 31 to move rearwardly from the hopper openings to permit the coal to flow onto the shelves 30. As soon as the arms of the wheels 46 disengage the levers, the upper ends of the latter are drawn rearwardly by the springs 59 and the plates are

caused to move inwardly to discharge the coal from the shelves into the stoker boxes.

The coal that is thus deposited in the stoker boxes is fed into the fire box by means of the shovels 32. Each of these shovels comprises a bar bent to form opposite side hangers 70—70' and a lower end connecting rod 71 on which is fixed a forwardly directed, V-shaped nose plate 72. The hangers are provided with trunnions 73 whereby the shovels 75 are swingingly suspended from the opposite side walls of the stoker boxes, and one of the hangers of each shovel, being the one at the right side, extends through the opening in the wall of the box to the outside and continues upward from the trunnion and is provided with a laterally extending flange 75, adapted to be engaged by the arms 45' of the wheel 45, and with an extension 76 above said flange whereto a spring 77 is attached to retain the shovel at its forward position when not actuated rearwardly by the arms of the wheel 45. Assuming then that the device is so constructed and operatively connected for operation, coal will be delivered through the tubes 8—10 and 12 by action of the worm conveyers into the hoppers 13 and 14.

Operation of the shaft 35 causes rotation of the wheels 46 and these acting upon the levers 56 cause reciprocation of the plates 31 to permit coal to be delivered onto the shelves 30 and then to be discharged thereby into the stoker boxes.

The parts are so arranged that, as the plates 31 come forwardly to deliver the coal into the stoker boxes, the shovels are drawn rearwardly, and after the coal has been pushed from the shelves, the shovels are released and are thrown forwardly against the coal by the tension of the springs 77 to cause the coal to be scattered and discharged into the fire box.

It is apparent that the provision of arms 45' of different lengths will cause more or less tension on the springs for the different discharging movements of the shovels, and this will cause distribution of the coal to different parts of the fire box. The shape of the shovel nose plates will also serve to scatter the coal so that it will be thrown equally to both sides of the fire box.

It is apparent that if it is desired, only one hopper can be used and different means of driving the conveyers could be used without departing from the spirit of the invention; therefore, I do not wish to be limited only to the particular construction illustrated.

Having thus described my invention, what I claim as new therein and desire to secure by Letters Patent, is:

1. In a stoking device of the class described, a stoker housing having an open end and a feed opening in the top thereof,

a shelf disposed horizontally within the housing below the feed opening, a slide plate mounted on said shelf to move across said feed opening, a shovel suspended with-
5 in the housing below said shelf having a suspending leg provided with a laterally extending flange, a driven shaft extending through the housing, wheels fixed on said shaft having radially extending arms there-
10 on, the arms of one of said wheels being adapted to engage said shovel leg flange to actuate the shovel rearwardly, a lever pivotally fixed to the housing adapted to be engaged at one end by the arms of the other

wheel and being operatively connected with 15 the slide plate so as to move the latter rearwardly, and springs fixed to the housing and connected with the shovel and plate, respectively, for moving said shovel and plate forwardly when released by said arms. 20

2. A device as in claim 1 wherein the arms of the wheel engaging the shovel leg flange, are of different lengths for the purpose set forth.

Signed at Seattle, Washington, this 20th 25 day of May, 1921.

JOSEPH STANLEY STOGDALE.
